UNITED STATES PATENT OFFICE.

WILLIAM N. HUNTER, OF BLANCHESTER, OHIO.

COMBINED HAND BAG AND GRIP.

Application filed March 1, 1922. Serial No. 540,320.

My invention relates to traveling bags and grips which are adapted to be folded so as to provide a lady's hand bag when it is desired to use the construction for that purpose.

The invention consists of that novel construction and arrangement to be hereinafter particularly pointed out and claimed, in which the stiff rectangular bottom portion of the grip may be folded up along one side and locked in folded position under a pocket flap on the outside of the grip, so that when folded it shall be of the size and appearance of the ordinary shopping bag for ladies' use.

In the drawings,

Figure 1 is a perspective view of the complete traveling bag.

Figure 2 is a similar view of the bag folded for a hand bag.

Figure 3 is a central vertical section of the bag as shown in Figure 1.

Figure 4 is a similar section of the folded bag.

The bag is constructed of leather, cloth, canvas, or other suitable material, with a rectangular bottom 1, reinforced by a sheet of stiff cardboard or other stiff material 2, to form a flat substantial bottom, with integral sides 3, 3, extended to form bellows fold ends along the median line 5 of which the sides are secured together, a triangular fold 6 being provided at the bottom.

The bottom is also provided with the bottom supports 4, one near each of the four corners and, when preferred, at the middle, so that the construction for the lower portion is exactly like the ordinary traveler's grip. The sides and ends, however, are extended upwardly considerably more than in the ordinary grip where it is desired to provide a lady's hand bag of the ordinary shape, although it will, of course, be understood that dimensions of the bag can be varied within wide limits to satisfy the requirements.

At the top, the upper edges are sloped off or beveled to reduce the dimensions of the opening at the top and to enhance the appearance. Secured at or near the top edge 7 of the bag on one side is a rectangular pocket 8 the width of the bag. This pocket

8 is free except at the top, and on the inner side of the pocket near the lower edge, fastening members 10, 10, are provided to engage with corresponding fastening members 12, 12, which are secured in proper position on the opposite side of the bag near the bottom. These fasteners are preferably snap glove fasteners.

When it is desired to convert the traveling bag into a lady's hand bag, the stiff bottom is folded upwardly along the side to which the pocket is attached and then folded again to bring the upper end of the fold under the pocket and the fasteners into engagement where they are locked together, and the original bag is converted into the hand bag.

The pocket member is provided with a flap locked shut by a fastener 13. The upper edge of the bag is reinforced with a double thickness of material or may be bound with a metal strip if desired. The handles 14, 14, are secured at the upper edge, and a flap or tongue 15 to be secured by a fastener 16 is also provided to close the bag. If desired, of course, a lock can be employed to engage and lock together the sides of the bag at the mouth, to be opened with a key. In order to retain the bag in a truly rectangular form and give it an appearance when fully open of an elongated hand satchel, I form a line of stitches 17 along each longitudinal fold. In this way I form a permanent crease along this line of fold, which in addition materially assists in the repeated folding up of the bag.

Having thus described my invention, what I claim as new and desire to secure by Letters Patent, is:

A hand bag of the character specified, comprising a body portion of flexible material, a flat, stiff, rectangular bottom therefor, said bottom foldable against the outer surface of the body portion, bringing a fold of the opposite side of the body outermost, and said bottom having substantially half the width of the length of the bag, whereby the stiff bottom acts as a guide in folding to reduce the length of the bag when folded to substantially half the length of the bag when extended, and means for securing the bottom in folded position.

WILLIAM N. HUNTER.
